UNITED STATES PATENT OFFICE.

WILLIAM J. CALLAWAY, OF SAN DIEGO, CALIFORNIA.

WAVE-MOTOR.

1,256,106.

Specification of Letters Patent.

Patented Feb. 12, 1918.

Application filed November 21, 1916. Serial No. 132,638.

To all whom it may concern:

Be it known that I, WILLIAM J. CALLAWAY, a citizen of the United States, residing at San Diego, in the county of San Diego and State of California, have invented new and useful Improvements in Wave-Motors, of which the following is a specification.

This invention relates to wave motors, 10 and contemplates certain improvements in my application for patent on a similar device, bearing Serial Number 838,545 and allowed April 11, 1916.

One of the chief characteristics of the invention resides in the provision of a weighted element adapted to rise and fall with the waves of the ocean or other large bodies of water and operatively connected with a shaft mounted for rotation, whereby the latter is actuated with the fall of the weighted element to generate power which can be utilized for operating dynamos or other machinery.

More specifically stated, the weighted element is in the nature of a receptacle divided into separate compartments designed for holding sufficient water to supply the desired weight, and a requisite amount of air to give the element as a whole the desired buoyancy, 30 with means for regulating the quantity of water in its respective compartment.

The invention further embodies a toothed wheel fixed upon the shaft mounted for rotation, with a chain connecting the toothed 35 wheel with the weighted element, the teeth of the sprocket wheel being disposed so that the chain will pass easily thereover when the weighted element is elevated with the rise of the waves, but engage the wheel to rotate the shaft with the fall of the weighted element.

Another object of the invention resides in the provision of an arrangement of a plurality of such elements associated with a 45 shaft in a manner whereby they are capable of independent operation with a view of maintaining the shaft in continuous rotation.

The invention also provides a means whereby the weighted elements can be held 50 in their highest position with a view of stopping the machinery of the plant, when the latter is in need of repairs or for any other purpose. This means is also susceptible for use in connection with any one of the weighted elements to hold the latter out

of the water at rest, while the remaining elements continue to operate.

With the above and other objects in view, which will appear as the nature of the invention is better understood, from the following description taken in connection with the accompanying drawings, the invention resides in the construction, combination and arrangement of parts as claimed.

In the drawings forming part of this specification like numerals of reference indicate similar parts in the several views and wherein:—

Figure 1 is a cross section taken through a power house wherein the present invention has been installed.

Fig. 2 is a perspective view of one of the weighted elements.

Fig. 3 is an enlarged detail section showing the means for locking the elements in their elevated position.

Fig. 4 is an elevation of the beam supporting the mechanism.

Before entering into a detail description of what is herein shown, I desire to have it understood that I do not limit myself to this particular arrangement, and that such changes may be resorted to when desired, as properly fall within the scope of what is claimed.

Referring to the drawings in detail A indicates generally the power house which may be of any suitable dimensions, and built upon pilings B a requisite distance from the shore. The floor of the power house is arranged at a height above the reach of the highest wave. Pilings 10 are arranged in pairs on each side of the power house, and any number of pairs of these pilings may be provided and are connected by a beam 11 which passes through the upper portion of the power house. Preferably there are several rows of the pilings 10 on each side of the power house which are connected by the beams 11.

Arranged between each pair of the pilings 10 is a weighted element, preferably in the nature of a tank 12 divided by a partition 13 into an upper compartment 14 and a lower compartment 15. The tanks 12 are arranged to slide between the pilings 10 and are suspended by a flexible element, such as a chain 16 of the roller type, the chain passing over an idler pulley 17 journaled in a suitable opening 18 in the beam 11, the chain extending across the top of the beam into the

power house A where it is trained over a toothed wheel 19 with its free end supporting a weight 20. It is to be borne in mind that the tanks 12 rise with the waves, the 5 teeth of the wheel 19 being so disposed to permit the chain to pass freely over said wheel during the upward movement of the tanks, while the weight 20 tends to hold the flexible element or chain taut during this 10 movement of the tank. As the tank 12 falls or gravitates with the fall of the body of water, the flexible element or chain 16 engages the teeth on the wheel 19 to impart a rotary movement to the shaft 21 upon which 15 the wheel 19 is keyed. The shaft 21 as will be noted is journaled in an opening 22 in the beam 11, and with the chain or flexible element 16 operates through the respective openings 18 and 22. There are of course two 20 of the shafts 21 journaled on each beam and arranged within the power house, with the free terminals of the chains or flexible elements from the opposite sides of the power house trained over the wheels 19 so that 25 these respective shafts are rotated in opposite directions. Attention is directed to the fact that the periphery of the toothed wheels 19 are arranged substantially in a plane with the upper surface of the beam 11 so 30 that the cross run of the flexible element or chain 15 is supported upon the beam and thereby prevented from sagging. The shaft upon which the toothed wheels 19 are fixed may be of any suitable length, and of a sufficient length to accommodate as many 35 toothed wheels as there are tanks or weights in operation on that particular side of the power house. While as above stated the power house may be of any suitable dimensions it is preferable to have the latter two 40 hundred or more feet long so that there will be two or more waves passing at all times thereby keeping the number of tanks or weights in action all the time which imparts 45 a constant power to each shaft. It is of course understood that the power developed in this manner may be utilized for various purposes such as for instance for operating 50 dynamos and other machinery.

The tank or weighted elements 12 on opposite sides is provided with upper and lower spaced pairs of rollers 25 which engage the pilings 10 to facilitate the adjustment of said elements with the rise and fall 55 of the body of water.

As above stated the compartment 14 is adapted to contain water to supply the desired weight to the tank, while the lower compartment 15 is filled with air, so that 60 when the tank is submerged in the water it possesses the proper buoyancy to rise instantly with each incoming wave. It is of course to be borne in mind that the quantity of water in the compartment 14 is changed 65 from time to time according to the height of

the waves from day to day, and for which purpose the tank is provided with an inlet opening 26 in the top thereof which is normally sealed by means of a closure 27 of any suitable character, while an outlet valve 28 70 is provided adjacent the bottom of the compartment 14. The compartment 15 is also provided with a valve 29 as shown. It is of course to be understood that the weight of the float will be made proportionate to the 75 work to be done, the float being just buoyant enough at all times to be raised by the waves. With a view of locking any one of the tanks 12 at the highest point to which the waves will raise said tank at any time during the operation of the device, I preferably employ a bolt 30 carried by the end of a vertically disposed rod 31 with which it has a hinged connection as at 32. The locking element is mounted for vertical sliding 80 movement through a bracket 33 arranged within the power house, while the bolt 30 is also arranged for a similar movement within a slot in the beam 11. In the normal position of the device the bolt 30 rests upon the bracket 33 with its beveled extremity below the upper surface of the beam 11. In use the bolt 30 is moved upwardly through the slot in the beam 11 with its beveled surface projected above the beam, and held in 90 this position by arranging the rod 31 upon a rest 34 arranged within the power house. The bolt 30 is beveled in the proper direction to permit the roller links of the chain 16 to ride over the bolt when the tank 12 is elevated, but the instant the tank starts to descend or gravitate to its lowermost position the chain 16 will be engaged by the bolt 30 thereby holding the tank in the highest position that any wave may lift it. It is of 100 course understood that one of these locking devices is provided for each of the tanks 12, whereby all of the tanks may be held in their highest position with a view of stopping the machinery of the plant, or in case any one 110 particular tank or its associated parts require attention or repair this particular tank can be held elevated out of the water while the remaining tanks continue in operation.

While it is believed that from the foregoing description the nature and advantages of the invention will be readily apparent I desire to have it understood that what is herein shown and described is merely illustrative of the preferred embodiment of the 120 invention to which I do not limit myself and that such changes may be resorted to when desired as fall within the scope of what is claimed.

What is claimed is:—

1. In a wave motor, a supporting structure embodying spaced parallel uprights, a float slidably fitted between said uprights to rise and fall with a body of water, a shaft journaled on the supporting structure, 135

- a sprocket wheel fixed thereon, a flexible element suspending the float and trained over said wheel to engage the latter and rotate the shaft with the fall of the float, a weight on the opposite end of the element for holding the latter taut with the rise of the float, a locking element adapted to be supported immediately beneath the flexible element and having a beveled edge to permit the flexible element to pass freely thereover during the rise of the float, and adapted to engage the flexible element to prevent the fall of the float from the highest point to which the waves will elevate the latter.
2. In a wave motor, a supporting structure embodying spaced parallel uprights, a float slidably fitted between said uprights to rise and fall with a body of water, a shaft journaled on the supporting structure, a sprocket wheel fixed thereon, a chain suspending said float and trained over said wheel to engage the latter and rotate said shaft with the fall of the float, a weight on the opposite end of the chain for holding the latter taut with the rise of the float, an element adapted to automatically engage said chain to hold the float at the highest point to which the waves will raise the latter, said element being mounted for vertical adjustment, and means for supporting said element in an active position whereby the chain will pass over the element with the rise of the float and be engaged by the latter at a predetermined interval.
3. In a wave motor, a supporting structure embodying spaced parallel uprights, a float slidably fitted between said uprights to rise and fall with the body of water, a shaft journaled on the supporting structure, a sprocket wheel fixed thereon, a chain suspending said float and trained over said sprocket to engage the latter and rotate said shaft with the fall of the float, a weight on the opposite end of the chain for holding the latter taut with the rise of the float, a pair of spaced brackets, a vertically adjustable element adapted to alternately engage said brackets to be supported in active and in inactive positions, said elements when in active position being adapted to automatically engage the chain to prevent the fall of the float from the highest point to which the wave will elevate the latter.
4. In a wave motor, a supporting structure embodying spaced parallel uprights, a float slidably fitted between said uprights to rise and fall with a body of water, a shaft journaled upon said supporting structure, a sprocket wheel fixed thereon, a chain suspending said float and trained over said sprocket to engage the latter to rotate said shaft with the fall of the float, a weight on the opposite end of the chain for holding the latter taut with the rise of the float, a pair of spaced brackets, an element normally supported upon one of the brackets in an inactive position, a rod depending from said element and normally disposed at one side of the other bracket, said rod being adapted to be positioned upon the latter mentioned bracket to elevate said element to an active position whereby it automatically engages the chain to prevent the fall of the float from the highest point to which the waves will elevate the latter, and said rod being hingedly connected with said element to permit the rod to be moved to an active or inactive position.

In testimony whereof I affix my signature.
WILLIAM J. CALLAWAY.
